CLAIM

The ornamental design for a floor stand for toilet paper and a toilet bowl brush, as shown and described.

DESCRIPTION

FIG. 1 is a front elevational view of a floor stand for toilet paper and a toilet bowl brush showing my new design;
FIG. 2 is a rear elevational view thereof;
FIG. 3 is a right side elevational view thereof;
FIG. 4 is a left side elevational view thereof;
FIG. 5 is a top plan view thereof;
FIG. 6 is a bottom plan view thereof;
FIG. 7 is a top, front, and left side perspective view thereof;
and,
FIG. 8 is an additional top, front, and left side perspective view thereof, with the broken-line disclosure of a toilet paper roll and toilet brush being for illustrative purposes only and forming no part of the claimed design.
